(57) **CLAIM**

The ornamental design for a battery compartment as shown and described.

DESCRIPTION

FIG. 1 is a top, front and right side perspective view of a battery compartment showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the battery compartment which form no part of the claimed design.
